UNITED STATES PATENT OFFICE

CHESTER A. SANBORN, OF LYNN, MASSACHUSETTS

DESIGN FOR A BUILDING

Application filed February 17, 1930. Serial No. 34,574. Term of patent 7 years.

To all whom it may concern:

Be it known that I, CHESTER A. SANBORN, citizen of the United States of America, residing at Lynn, in the county of Essex and State of Massachusetts, have invented a new, original, and ornamental Design for Buildings, of which the following is a specification, reference being had to the accompanying drawings, forming a part thereof.

Figure 1 is side elevation of the building.
Figure 2 is a top plan view thereof.
Figure 3 is an end view of the building.
Figure 4 is an opposite end of the building.
I claim:

The ornamental design for a building as shown.

CHESTER A. SANBORN.
